APPARATUS FOR TREATING MASONRY STRUCTURES

Louis S. Wertz, Shaker Heights, Ohio

Application October 28, 1931. Serial No. 571,595

5 Claims. (Cl. 72—128)

My invention particularly relates to the repairing of defective areas within the interior of masonry structures and to the strengthening of such structures. These interior areas may become defective subsequent to the installation of the structure, due to water leakage or other unfavorable conditions, or they may be defective as the result of conditions at the time of installation, such as a poor mix, improper pouring, forming of porous areas for various reasons, etc. Thus, from many causes, the interiors of masonry structures become honeycombed with water and air pockets and seamed with leakage channels, evidences of which upon the surfaces of the structures are no more definite than that there is surface leakage. Oftentimes, the leakage channels have their source in soil back of the masonry structure and traverse the full width of the structure, encountering and crossing interior pockets on the route from the rear to the front of the structure. It is the object of my invention by an improved process and improved means for carrying out the process, to fill these pockets and channels with grout or other repair material forced thereinto, and then to complete the repair operation by plugging the cavity and the repair hole through which the grout has been forced into the structure. The working of the invention also strengthens the structure upon which it is practiced. The claims of this application are limited to the improved apparatus for treating masonry structures.

Preferably I incorporate with the grout which I utilize for the repair operation some desirable waterproof material, and for this material I prefer to use iron filings which since they oxidize possess a natural affinity for the concrete. Preferably, also, the grout material is mixed with a liberal percentage of water which gradually evaporates and would leave parts of the masonry voids unfilled except that the waterproofing material, such as the iron filings, expands due to oxidation, as the water evaporates and preserves the filled condition of the cavities.

The invention herewith presented differs from that described and claimed in United States Patent No. 1,726,600, issued upon my improved process of treating masonry surfaces in that in said patented process, air is depended upon as the vehicle for carrying the repair material, and the repair material is projected against the exterior of the masonry surface and into surface pits thereof; whereas, in the present invention, the repair material is conveyed by any suitable and sufficient forcing medium, and is forced into

the masonry structure from the interior thereof.

My invention particularly relates to processes of and means for repairing masonry structures which will be of more economical construction and operation than present apparatus and processes with which I am acquainted, and which will be of more convenient operation.

The annexed drawing and the following description set forth in detail certain steps illustrating my improved process and certain means exemplifying my improved apparatus, such steps and means constituting, however, but a few of the various series of steps by which the improved process may be carried out and but one of the various forms in which the principle of the improved apparatus may be embodied.

In said annexed drawing:

Figure 1 is a partial elevation and a partial axial section of my improved apparatus shown detached from a section of masonry structure upon which the apparatus is designed to operate to effect the repair of defective and impaired portions therein and to strengthen the structure;

Figure 2 is an end view, taken from the plane indicated by the line 2—2, Figure 1;

Figure 3 is a portion of Figure 1, upon an enlarged scale;

Figure 4 is a view similar to Figure 1 showing the improved apparatus operatively connected with the masonry structure, the latter having already been operated upon by the apparatus and being shown in repaired and strengthened condition;

Figure 5 is a portion of Figure 4, upon an enlarged scale;

Figure 6 is a vertical section, taken in the plane indicated by the line 6—6, Figure 5; and

Figure 7 is a view, upon the same scale as that of Figure 5, showing a fragmentary portion of the completely repaired and strengthened masonry structure in finished condition.

Referring to the annexed drawing in which the same parts are indicated by the same respective numbers in the several views, a masonry structure 1 is shown as having interior defective areas such as the pockets 2 and fissures 3. For effecting the repair of these defective areas and strengthening the structure, a longitudinal hole 4, Figure 1, is drilled in the structure 1 whereby the material most deteriorated is removed, the pockets 2 and fissures 3 within the general area under repair communicating with this hole 4, and the latter being adapted to accommodate the improved mechanism which I provide for forcing the repair material into the defective areas.

This hole 4 is made in the structure from a surface position which shows material water leakage. When the interior defective condition of the structure is manifestly quite extensive, as evidenced by considerable surface leakage over a large surface area, a plurality of these repair holes 4 will be made and a corresponding number of distinct repair operations effected.

The repair mechanism includes an open-ended 10 pipe 5 having an externally-threaded outer end 6 with which a nut 7 engages, there also being provided a sleeve 8 adapted to surround the central portion of the pipe 5 and having an inner-end handle member 9. The nut 7 forms a stop at 15 the outer end of the pipe 5, for a purpose hereinafter fully explained, and is formed with terminal flat portions 7' for engagement with a suitable wrench. A portion of the exterior surface of the pipe 5 is threaded to co-operate with 20 an internally-threaded portion of the sleeve 8, the pipe 5 extending inwardly of the handle 9 of the sleeve 8 and having also a handle 10 welded thereto, the extreme inner end of the pipe 5 being adapted to engage with a threaded bore upon 25 one side of a valve body 11. The other side of this valve body 11 is connected to one part 12 of a two-part coupling member whose other part 12' connects with a pipe 26 which communicates with the supply of repair material (not shown). 30 The body 11 forms a seat for the control mechanism 13 of the valve. When the handle 9 is turned to move the sleeve 8 longitudinally of the pipe 5, the handle 10 is manually restrained from moving, which restraint obviates the displacement of the pipe 5 from the body 11 and also 35 prevents the movement of the pipe 5 with the sleeve 8.

The repair hole 4 in the structure 1 is made somewhat greater in diameter than the 40 diameter of the sleeve 8 so that this sleeve and the nut 7 can be readily inserted in the hole 4 and an annular space 25 remains between the wall of the hole 4 and the outer surface of the sleeve 8. In order to prevent escape of repair material 45 through the space 25 from the inner end of the hole 4, when material is being forced through the pipe 5, I utilize a rubber, tubular cylindrical member 20 surrounding the pipe 5 between the nut 7 and the outer surface of a collar 17 loosely 50 mounted upon the conveyor 5 adjacent the outer end of the sleeve 8, as shown in Figure 3. This tubular rubber member 20 is laterally expanded, as shown in Figure 5, when compressed by the threaded movement of the sleeve 8 longitudinally 55 of the conveyor 5, and thus subdivides the space 25 and prevents the movement of repair material from the inner end of the hole 4 through the space 25.

The feed-pipe 5 is formed with an annular 60 series of holes 19, more or less staggered, or at least not all in the same plane perpendicular to the axis of the conveyor 5, which holes 19 are adapted to communicate with radial holes 18 in the collar 17, and hence also with an annular 65 groove 18' formed in the interior surface of the collar 17 and communicating with the holes 18. When the apparatus is assembled and tightened for working conditions, as seen in Figure 5, the 70 repair material is forced into and through the pipe 5 and escapes through the holes 19 and 18 and also escapes from the outer end of the conveyor 5, and thus fills the pockets 2 and fissures 3 in the masonry structure communicating with the hole 4, and also fills the space 25 around the 75

sleeve 8 and the inner end of the hole 4, all as clearly shown in Figure 5.

In order that the repair material thus being forced into the masonry structure 1 may not escape from the front of the structure and yet 80 may be forced into the fissures and pockets communicating with the front surface of the structure, I provide a face plate 14 loosely surrounding the sleeve 8 and adapted to be resiliently spaced from the face of the masonry structure 1 by an 85 annular rubber collar 15 seated in a groove formed in the inner face of the plate 14 and extended from said inner face, this face plate 14 being tightened against the face of the masonry structure 1, after the repair mechanism is in position, 90 by means of a nut 16 co-operating with the externally threaded sleeve 8. The space 27 between the outer surface of the masonry structure 1 and the inner face of the plate 14 permits repair material to escape from the space 25 into the space 27 95 whence it is forced into the fissures 3 which intersect the surface of the structure 1.

The process effected by the improved apparatus shown in the accompanying drawing and previously described is worked as follows. The repair hole 4 is cored out of the structure 1 and in 100 a defective area thereof, as indicated by the leakage conditions upon the surface of the structure 1, which hole 4 intersects a number of the pockets 2 and fissures 3 of the area to be repaired. 105 Then the pipe 5 and associated elements are inserted in the hole 4, in the manner suggested by Figure 1 and to the extent desired, preferably within a few inches of the inner end of the hole 4. The handle 9 is then operated to move the sleeve 110 8 and the collar 17 inwardly of the structure 1, thus expanding the rubber annulus 20 in the manner clearly shown in Figure 5, locking or anchoring the pipe 5 and associated parts in the hole 4, and bringing the ports 18 of the collar 17 into 115 registry with the ports 19, or some of said ports 19, in the pipe 5. The face plate or shield 14 is then rigidly tightened against the surface of the structure 1 by means of the nut 16. The repair material is then fed under high pressure into and 120 through the tube 5 whence it flows into the inner end of the hole 4 through the open end of the tube, and into the space 25 through the ports 19 and 18, and into the space 27 between the front wall of the structure 1 and the face plate 14. 125 These various chambers into which the repair material is thus forced provide for the feeding of this material into and through the various pockets 2 and fissures 3 which communicate with the hole 4 or communicate with that part of the front face 130 of the structure 1 which is under repair. After the repair material has properly set, the handle 9 is operated to back off the sleeve 8 and permit the rubber annulus 20 to contract, when the repair apparatus can be removed from the hole 4. That 135 part of the hole 4 which was occupied by the repair apparatus is then plugged with repair material 28, and the surface of the structure 1 which was covered by the face plate 14 trimmed so as to 140 present the neat and smooth appearance shown in Figure 7. Thus, the defective and leaky areas of the structure are repaired, and the structure is strengthened due to the filling of the internal voids thereof.

I direct particular attention to the convenient operation and economical manufacture of the apparatus shown and described. It will be particularly noted that when such apparatus is removed from the repair job, there are no working parts 145

left in the job; hence, no added cost by reason of the loss of repair parts.

I further direct particular attention to the fact that the iron filings, or other waterproofing material with which the grout is associated, are forced into the interior of the structure under repair, and not merely thrown or sprayed or otherwise forcibly projected against an exterior surface of the structure.

10 The repair material such as grout in a creamy condition, and the oxidizable material and a preponderant portion of water, are forced into the structure under repair by any suitable forcing means which develops sufficient pressure, and one such suitable forcing medium is compressed air. The oxidizable material, which preferably is iron filings, is forced into the structure in substantially pure state; that is, before it has been partially chemically acted upon, or oxidized. This oxidizable material is so associated with the other agents that oxidation takes place very rapidly. The particles of iron expand within the pores and cavities of the structure to completely fill the same. If desired, a suitable oxidizing accelerator, such as ammonium chloride, sodium chloride, hydrochloric acid, and alum, may be utilized so as to insure the quick and effective oxidation of the iron particles.

30 What I claim is:

1. Apparatus for treating masonry structures comprising a tubular conveyor; a sleeve therefor and movable longitudinally thereof; a stop member upon the conveyor; and a laterally-expansible member surrounding said conveyor between one end of said sleeve and said stop member.

2. Apparatus for treating masonry structures comprising a tubular conveyor; a sleeve therefor and movable longitudinally thereof; a stop member upon the conveyor; and a tubular rubber

block surrounding the conveyor between one end of said sleeve and said stop member.

3. Apparatus for treating masonry structures comprising a tubular conveyor having an operating handle; a sleeve surrounding said conveyor and having screw-threaded engagement therewith and having an operating handle; a nut secured upon the end of said conveyor; and a tubular rubber block surrounding the conveyor between one end of said sleeve and said nut.

4. Apparatus for treating masonry structures comprising a tubular open-ended conveyor formed with a series of wall discharge ports; a stop member secured exteriorly of and adjacent one end of the conveyor; a collar surrounding the conveyor, movable longitudinally thereof, and having a series of ports adapted to communicate with the conveyor ports; a laterally expandable member between said stop member and said collar; and a sleeve having screw-threaded engagement with the conveyor and adapted to move said collar to expand the expandable member and to bring said ports into registry.

5. Apparatus for treating masonry structures comprising a tubular open-ended conveyor formed with a series of wall discharge ports; a stop member secured exteriorly of and adjacent one end of the conveyor; a collar surrounding the conveyor, movable longitudinally thereof, and having a series of ports adapted to communicate with the conveyor ports; a laterally expandable member between said stop member and said collar; a sleeve having screw-threaded engagement with the conveyor and adapted to move said collar to expand the expandable member and to bring said ports into registry; a face plate surrounding the sleeve and movable longitudinally thereof; and means for locking the face plate in adjusted position.

LOUIS S. WERTZ.
